UNITED STATES PATENT OFFICE.

FRANK R. LAY, OF INDIANAPOLIS, INDIANA, ASSIGNOR TO THE PERFECTION BROOM COMPANY, OF INDIANAPOLIS, INDIANA.

MOP.

SPECIFICATION forming part of Letters Patent No. 739,786, dated September 22, 1903.

Application filed April 10, 1903. Serial No. 152,063. (No model.)

To all whom it may concern:

Be it known that I, FRANK R. LAY, a citizen of the United States, residing at Indianapolis, in the county of Marion and State of Indiana, have invented a new and useful Mop, of which the following is a specification.

The invention relates to mops, and has for its object to provide a simple, inexpensive, and efficient device of this class whereof the parts may be assembled with facility and at small cost and in which the strands or other suitable flexible material comprising the rubbing-surface of the head are securely held against displacement or detachment and the fastening means therefor covered to prevent contact thereof with adjacent objects in any position in which the mop may be used.

Further objects and advantages of this invention will appear in the following description, and the novel features thereof will be particularly pointed out in the appended claims, it being understood that various changes in the form, proportion, and the minor details of construction may be resorted to without departing from the spirit or sacrificing any of the advantages of this invention.

In the drawings, Figure 1 is a view of a mop constructed in accordance with the invention with the strands separated to show the fastening means therefor. Fig. 2 is a plan view showing the first step in the operation of constructing or assembling the parts of the mop. Fig. 3 is a view showing the engagement of the extremities of the band, constituting the second step in the operation of constructing the mop. Fig. 4 is a longitudinal sectional view showing the parts after the introduction of the spreader, which is here shown formed on one end of the handle. Fig. 5 is a transverse sectional view taken in the plane of the fastening devices.

Similar reference characters indicate corresponding parts in all the figures of the drawings.

In the preferred embodiment of the invention the flexible material of the head consists of loosely-twisted strands of cotton or like material of a form well known in the art, the same being indicated in the drawings by the numeral 1, and in the construction of the mop

the number of strands or quantity of other flexible material necessary to form one mop (and preferably determined by weight) are disposed centrally upon the transverse flexible band 2, as shown in Fig. 2, after which the extremities of the band are brought together around the strands and are interlocked by means of the tongues or reversely-bent terminals 2^a thereof, as shown in Fig. 3.

These reversely-bent terminals overlap each other and are provided with alining perforations, through which a fastening device is passed and driven into the core or spreader now to be described and which will prevent any tendency of the terminals to separate. A tapered spreader or core 3 is then inserted into the center of the encircled strands, which are thus compressed transversely at the centers of their lengths and in the plane of the band, while the portions thereof at opposite edges of the band are correspondingly bulged to overlap said edges, and thus prevent subsequent shifting of the strands in the band and acting as pads to prevent said edges coming in contact with adjacent objects.

The band is then secured to the spreader or core by means of pins, nails, or analogous fastening devices 4, each of which is preferably driven through openings 5 in one side of the band and centrally through the core and spreader and also through the interposed mass of strands and terminally bent or clenched against the opposite side of the band to prevent accidental displacement. These nails, pins, or fastening devices are alternately arranged in different transverse planes, and one of them is extended through the interlocking tongues or overlapped extremities of the band to prevent accidental disengagement thereof. In practice the spreader or core preferably is formed by a tapered extremity of the mop handle or staff 6.

After the fastening of the band to the spreader the portions of the strands which are above and below the plane of the band are left free to fall loosely over the band to conceal the latter, and thus prevent contact thereof with adjacent objects in whatever position the mop may be used. It will be noted that in either the depending or elevated position of the mop-head, as when the head is either below

or above the other end of the handle or staff, the free extremities of the strands at one side of the plane of the band will fall over the latter, and therefore whether the mop is being used in scrubbing the floor or washing windows the band will be concealed and prevented from breaking or marring objects with which the mop-head may come in contact.

Having described the invention, what is claimed is—

1. A mop-head consisting of a band, a spreader, and flexible material interposed between the band and the spreader and clamped therein at an intermediate point with the portions thereof on opposite sides of the band free to fall over and cover said band.
2. A mop-head comprising flexible material compressed at an intermediate point, an encircling band disposed therearound at the point of compression with the material bulging over the edges thereof, and a spreader ar-

ranged within the material in said band to bind them securely together, the material being unrestricted on opposite sides of the band to permit its ends to fall over and cover said band.

3. A mop-head having a band, a spreader arranged therein, flexible strands interposed between the spreader and the band, the latter being provided with interlocked extremities, and fastening devices securing the band to the spreader, one of said fastening devices extending through the interlocked extremities of the band.

In testimony that I claim the foregoing as my own I have hereto affixed my signature in the presence of two witnesses.

FRANK R. LAY.
